UNITED STATES PATENT OFFICE

WLADYSLAW JASINSKI, OF CHICAGO, ILLINOIS

UTILITY FOLDING BED

Application filed May 10, 1929. Serial No. 362,068.

This invention relates to certain new and useful improvements in folding beds and has for its primary object to associate a folding bed with an article of furniture such as 5 a bedroom dresser or chest of drawers, a trunk, a living-room chair or similar article of furniture, whereby the bed when in folded condition is completely confined within the article of furniture and hidden from 10 view.

Another object of the invention is to provide a folding bed associated with an article of furniture comprising a hinged frame formed of a plurality of sections embodying 15 side rails, supporting legs and bracing links adapted when folded to lie adjacent each other for confinement within a minimum of space when housed within the article of furniture.

With the above and other objects in view that will become apparent as the nature of the invention is better understood, the same consists in the novel form, combination and arrangement of parts hereinafter more fully 25 described, shown in the accompanying drawings and claimed.

In the drawings:—

Figure 1 is a perspective view of the folding bed associated with a trunk or box structure with the skeleton bed frame extended in set-up operative position;

Figure 2 is a perspective view of the folding bed shown in Figure 1 illustrating a pad supporting canvas stretched between 35 the side rails of the folding bed frame;

Figure 3 is a top plan view of the folding bed shown in Figures 1 and 2, detached from the trunk or box structure;

Figure 4 is an enlarged side elevational 40 view of the bed frame in folded position and removed from the trunk, showing the relationship between the several hinged links when in folded position;

Figure 5 is a perspective view of the bed 45 in folded position and disposed above the trunk to be lowered therein;

Figure 6 is a vertical cross-sectional view through the trunk with a part of the folded bed frame illustrated;

Figure 7 is a detail sectional view taken

on line 7—7 of Figure 6 showing the guide within the trunk for the sliding bed frame;

Figure 8 is a perspective view of one of the end strip supporting hooks;

Figure 9 is a vertical longitudinal sectional view of an article of furniture, such as a living-room chair or the like with a folded bed confined within the furniture frame beneath a seat pad;

Figure 10 is a perspective view of the article of furniture shown in Figure 9 with the bed frame in its extended set-up condition;

Figure 11 is a perspective view of the chair pad removed from the chair;

Figure 12 is a perspective of the extended folded bed associated with a chest of drawers or a bed-room dresser;

Figure 13 is a detail sectional view of the lower end of the dresser showing the folded bed confined therein;

Figure 14 is a detail sectional view of a part of the dresser showing a guide roller on the inner end of the folding bed frame confined within a slotted guide;

Figure 15 is a fragmentary perspective view showing the guide for the bed frame;

Figure 16 is a side elevational view of the bed frame in partly collapsed position;

Figure 17 is a fragmentary perspective view 80 of a part of the frame;

Figure 18 is a perspective view of a leg; and

Figure 19 is a perspective view of one of the link brackets.

In the form of the invention illustrated in 85 Figures 1 to 8, the reference numeral 1 designates a trunk body provided with a hinged cover 2, a folding bed frame being associated with the trunk to be confined therein when out of use and in folded condition. The folding bed comprises a plurality of side supporting legs 3 carrying floor engaging feet 4, the oppositely positioned legs 3 at each side of the bed frame being connected by horizontal brace rods 5 and crossed brace rods 6 extending from points adjacent the upper ends of the side legs 3 to points at opposite sides of the center of the horizontal cross brace 5 as clearly shown in Figure 1.

The upper side rails of the bed structure 100

comprise crossheads 7 anchored to the upper angle end 3^a of each leg 3 as shown in Figure 18, with a pair of rail sections 8 between adjacent ends of the cross heads 7 between each pair of side legs 3. The rail sections 8 are hinged as at 9 at their outer ends to the cross heads 7 to swing downwardly while adjacent ends of the rail sections 8 are hinged together at 10 at the upper sides thereof to permit 10 downward swinging movement of the rail sections. Diagonal brace bars extend between the side legs 3 and adjacent ends of the rail sections 8, the bracing links 11 having a hinge connection 12 at adjacent ends to limit pivotal 15 movement thereof in one direction, the outer end of the lower link being pivotally connected as at 13 to the cross arm 13^a and having a bevelled lower end 11^a abutting the leg 3 to brace the links 11 on the leg 3, while the upper end of the upper link 11 is hingedly connected to the adjacent rail section 8. The upper hinge connection for the upper link 11 comprises an angle bracket 11^b, shown in Figure 19, that is anchored to the rail section 8 20 and to which the link is pivoted, the upper end of the upper link also being bevelled or diagonally formed to engage the rail section for bracing the links. Brace links 14 connect the lower ends of the side legs 3, the same being pivoted at their outer ends as at 15 to said legs, while the adjacent ends thereof are pivotally connected together as at 16 in a manner to permit limited swinging movement in one direction as will be clearly understood 25 from an inspection of Figure 1. When the folding bed frame is extended in its step-up position as shown in Figure 1, a strong and substantial construction results with the legs 3 rigidly positioned and maintained against 30 any collapsing movement.

End extension top rails 8^a are hinged as at one end as at 9^a to the end plate 7 of the side supporting legs 3 adjacent the trunk body 1 with the other ends of the extensions 45 8^a hinged as at 17 to a guide block 18 vertically slidable in a perpendicular corner guide 19 set into a corner of the trunk body 1 for purposes presently to appear. The corner posts 20 of a headrest are hinged at 50 their lower ends as at 21 to the adjacent ends of the top rail extensions 8^a, being connected by cross-slats 22 while brace links 23 hinged together at their adjacent ends as at 24 are connected at their outer ends as at 25 and 26 55 to the upper ends of the posts 20 and rail extensions 8^a respectively.

A canvas or other fabric sheet 27 is stretched between the upper side rails of the folding bed for the support of a bed pad. 60 mattress or the like and the clip 28 shown in detail in Figure 8 is employed for supporting the fabric sheet 27 in its operative position. The clip 28 has an angle end 29 engageable over the outer side edge of each 65 upper side rail with the opposite inner end

of the clip provided with a hook 30 to be received in an adjacent eye in the edge of the fabric sheet. The clips 28 are supported at the upper sides of the side rail as shown in Figure 2 with the fabric sheet 27 maintained in a substantially stretched and taut condition for the support of suitable bedding. 70

When it is desired to collapse the foldable bed and place the same in the trunk body 75 1 from its operative set up position shown in Figures 1 and 2, the head rest is collapsed by moving the links 23 upon their hinged connection 24 so that the head posts 20 may swing forwardly and downwardly to lie upon the end extensions 8^a of the upper side rails. The several links 11 and 14 are moved on their pivotal connection while the rail section hinges are collapsed so that the side supporting legs 3 may be moved to positions adjacent each other as shown in Figure 4. The collapsed bed structure is then shifted to a position overlying the trunk body 1 as shown in Figure 5 and thereafter lowered into the trunk body and at which time, the guide 80 blocks 18 slide downwardly in the guides 19. 85

In the form of the invention shown in Figures 9 to 11, the folding bed is associated with an article of furniture, such as a living-room chair or the like, the chair 32 as shown in Figure 10 having the seat cushion 33 removed, the folding bed frame being of a construction similar to the form of the invention shown in Figures 1 to 8 with the exception that the end extensions 8^b of the upper side rails are hingedly connected at their inner ends as at 34 to the forward side portions of a U-shaped frame 35 that is supported upon springs 36 normally forming the resilient support for the seat cushion 33 as shown in Figure 9. The front drop board 37 of the chair when in its closed position as shown in Figure 9 carries coil springs 36^a for the resilient support of the seat cushion. The bed frame is illustrated in Figure 10 in its extended set-up position to receive the fabric sheet 27 shown in Figure 2 for the support of bedding. When the bed frame is folded as illustrated in Figure 9, the upper end of the bed frame is confined within a pocket formed in the bottom of the seat cushion 33, while the upper side rail sections are confined between the spaced lugs 38 at the sides of the frame 35. 100 105 110 115

In the form of the invention shown in Figures 12 to 15, the folding bed frame is associated with an article of bed-room furniture, such as a dresser or chest of drawers, the furniture article 39 having a lower compartment 40 closed by hinged doors 41 for housing the bed frame. The folding bed frame is of the same construction as illustrated in Figures 1 to 11 with the inner rail extensions 8^c carrying lateral guide rollers 42 positioned in horizontal guides 43 carried by the inner 120 125 130

walls of the compartment 40. Also, the side supporting legs 3 carry roller casters 4^a to facilitate positioning of the folding bed in the article of furniture and removal thereof.

In each form of the invention, the folding bed is completely hidden from view when out of use and occupies a minimum of space in the article of furniture with which the same is associated. The brace bars between the opposite side legs as well as the legs at each side of the bed and also the brace bars between the upper rail sections provides a rigid bed structure when the same is set up for use. While clips 28 of the type shown in Figure 8 are illustrated for supporting the fabric sheet between the upper side rails of the bed, it is to be understood that the fabric sheet may be stitched at its longitudinal edges to the upper side rails to be folded with the bed frame.

While there are herein shown and described the preferred embodiments of the present invention, it is nevertheless to be understood that minor changes may be made therein without departing from the spirit and scope of the invention as claimed.

I claim:—

1. In combination with an article of furniture, a folding bed formed of hinged sections to occupy a space within the article of furniture, said bed comprising side legs, top rails formed of hinged sections foldable downwardly, brace rods between the top rail sections and the side legs, a hinged extension of the top rails connecting the bed to the article of furniture, and a collapsible head rest on the top rail extensions.

2. In combination with an article of furniture, a folding bed formed of hinged sections to occupy a space within the article of furniture, said bed comprising side legs, top rails formed of hinged sections foldable downwardly, brace rods between the top rail sections and the side legs, hinged brace rods between the legs at each side of the bed, rigid brace bars between the legs at opposite sides of the bed, a hinged extension of the top rails connecting the bed to the article of furniture, and a collapsible head rest on the top rail extensions.

3. In combination with an article of furniture, a folding bed formed of hinged sections to occupy a space within the article of furniture, said bed comprising side legs, top rails formed of hinged sections foldable downwardly, brace rods between the top rail sections and the side legs, a hinged extension of the top rails connecting the bed to the article of furniture, a collapsible head rest on the top rail extensions, a fabric sheet secured at its edges to the upper side rails, and a slotted guide connection between the article of furniture and attached end of the bed frame.

In testimony whereof I affix my signature.

WLADYSLAW JASINSKI.
